[57] CLAIM

The ornamental design for a video display terminal, as shown and described.

DESCRIPTION

FIG. 1 is a top, front leftside perspective view of a video display terminal showing my new design.

FIG. 2 is a top front perspective view thereof;

FIG. 3 is a rear elevational view thereof; and

FIG. 4 is a top plan view thereof.

The right side elevational view is a mirror image of the left side elevational.

FIG. 1.

Fig. 2.

FIG. 3.

Fig. 4.
